UNITED STATES PATENT OFFICE.

WILLIAM F. HUNT, OF NEW BRIGHTON, NEW YORK, ASSIGNEE TO C. W. HUNT COMPANY, OF WEST NEW BRIGHTON, NEW YORK, A CORPORATION OF NEW YORK.

STORAGE OF COAL, ORES, &c.

1,026,444.

Specification of Letters Patent. Patented May 14, 1912.

Application filed July 25, 1911. Serial No. 640,524.

To all whom it may concern:

Be it known that I, WILLIAM F. HUNT, a citizen of the United States, residing at New Brighton, Richmond county, Staten Island, State of New York, have invented certain new and useful Improvements in the Storage of Coal, Ores, &c., of which the following is a specification, reference being had to the accompanying drawings, which form a 10 part hereof.

It is now a common practice to store coal, ores, etc., in very large quantities, reaching many thousands of tons, at points remote from the mines but convenient for distribution. According to the simplest and most economical methods of handling the coal or other material, as practised hitherto, the material is brought to the place of storage in railway cars, is taken out of the cars by 20 steam shovels, scoops or buckets, raised to a suitable height, usually above a movable bridge, dumped from the shovel, scoop or bucket into a tram-car which travels on the bridge and is run out to the point at which 25 the contents are to be discharged, and is then dumped from the tram-car. There are thus no less than three distinct handlings or breakages of bulk of the material, each of which of necessity adds to the cost of storage. Furthermore, in the case of coal, very 30 serious loss in value is occasioned by the breaking of the pieces of coal not only at each of the several handlings, but especially in the dumping of the coal from the tram- 35 car. When the pile of coal below the bridge is low, the coal falls through a very considerable distance from the tram-car until it strikes the bottom of the storage yard or the coal thereon, and therefore acquires considerable velocity and has a considerable impact. When the pile of coal is high, the 40 coal which is dumped on top of the pile does not fall so far, but more or less of it rolls down the inclined side of the dump and 45 while the velocity of any piece is not very great, each piece makes many impacts before it comes to rest. It has been found that the breakage of coal in this manner is in more or less direct proportion to the velocity of its fall and to the number of impacts, and it is well known that the shrinkage in value from this cause is serious.

One object of the invention, therefore, is to effect a reduction in cost of storing coal, 50 ores, etc., by reducing the number of han-

dlings or breakages of bulk to a minimum, and also to reduce as much as possible the shrinkage in value of coal due to reduction in size through breakage.

In accordance with the invention the railway car in which the coal or other material is delivered at the storage yard, is itself run upon a suitable cage or platform to which it is secured, and the cage (as it is commonly called and will be called hereinafter) is 60 hoisted with the car and its contents and transported bodily to the point of discharge, where it is lowered to a point just above the top of the pile or dump, and the contents of the car are then discharged, preferably by 65 overturning the cage and car sufficiently to permit the discharge of the coal or other material. There is therefore only one handling or breakage of bulk of the coal or 70 other material between the railway car and the storage pile, with a consequent reduction of cost of storage and a great reduction of loss through reduction of size of coal, by 75 reason of the elimination of further handlings, together with a still further reduction of such loss by reason of the reduction of the height through which the coal falls or rolls. It will be understood, of course, 80 that in the storage of large quantities the coal or other material is first dumped in a 85 comparatively thin stratum over a large area and that successive strata, also of large area are formed so that there is no opportunity for the coal to roll down the sides of a high dump, except at the margins of the storage 90 pile.

The invention will be more fully explained hereinafter with reference to the accompanying drawing in which is illustrated a convenient form of apparatus with 95 which the invention may be practised and in which it is in part embodied.

In the drawing Figure 1 is a view partly in side elevation but more or less diagrammatic, illustrating a desirable form of apparatus for the practice of the invention. Fig. 2 is a view of the same in end elevation.

The railway car *a* in which the coal or other material to be stored is brought from the mine or other point is run directly upon a cage *b* of suitable construction, to which the car is secured by locking devices of any suitable character, indicated generally at *b'*. The cage *b* is suspended, as by chains *c c'*, 105 from a movable crane *d* which is provided 110

with suitable hoisting devices, indicated at 45
e, and is mounted movably on a bridge f,
which is itself movable over the storage
yard, being mounted upon legs g which are
themselves provided at their lower ends
5 with trucks h, which rest upon tracks i. The
legs g may have connected thereto in any
suitable manner, as by arm g', short in-
clined sections g² of track which are mov-
able with the bridge so as to facilitate the
10 placing of the railway car a on the bridge.

In operation the railway car, in which the
coal or other material is brought from the
mine or other point, is run directly upon the
15 cage and is secured thereto. By the hoisting
devices e the cage, with the car and its con-
tents, is then raised to a suitable height so
that the cage shall clear the top of the ma-
terial already deposited in the storage yard,
20 and is transported to the point at which the
carload is to be discharged. When that
point is reached the cage is lowered as close
as practicable to the surface of the material
already placed in the yard and the car is
25 then dumped, preferably by taking up the
hoisting ropes or chains e, on one side of the
cage, and lowering away the hoisting ropes
or chains e' on the other side of the cage.
The material is thus discharged from the
30 car without any other handling or breaking
of bulk and with the minimum of impact of
the pieces, so that breakage of the pieces is
also reduced to a minimum.

The drawing shows a traveling crane or
35 trolley with hoisting engines mounted there-
on, but it will be understood that the hoist-
ing mechanism may be arranged as may be
most convenient.

The coal or ore may be reclaimed for re-
40 shipment by any suitable apparatus.

It will be obvious that the form of the
apparatus employed may be varied to suit
different conditions of use and that the
invention, therefore, is not limited to the

particular apparatus shown and described 45
herein.

I claim as my invention:—

1. Apparatus for storing coal, etc., from
railway cars comprising a bridge, a trolley
mounted thereon, a cage suspended from the
50 trolley and adapted to receive a railway car,
means to hoist the cage and means to impart
a rotary movement to the cage and car
whereby the contents of the latter are dis-
charged.

55 2. Apparatus for storing coal, etc., from
railway cars comprising a bridge, a trolley
mounted thereon, a cage suspended from the
trolley and adapted to receive a railway car,
means to hoist the cage and means to impart
60 a rotary movement to the cage and car about
their longitudinal axis whereby the contents
of the car are discharged.

3. Apparatus for handling coal, etc., from
railway cars comprising a cage, a trolley 65
mounted on a bridge and having two sets of
hoisting mechanisms, a cage adapted to re-
ceive a railway car, and hoisting ropes con-
nected to the cage on opposite sides and to
the several hoisting mechanisms, whereby 70
the car with its contents may be hoisted,
transported to the point of discharge, and
discharged of its contents.

4. Apparatus for storing coal, etc., from
railway cars comprising a bridge, a trolley 75
mounted thereon, a cage suspended from the
trolley and adapted to receive a railway car,
mechanism carried on said trolley to hoist
the cage and to impart a rotary movement
to the cage and car whereby the contents of 80
the latter are discharged.

This specification signed and witnessed
this 24th day of July, A. D., 1911.

WILLIAM F. HUNT,
